PROCESS OF RECOVERING AND UTILIZING THE VALUABLE COMPOUNDS IN SPENT COOKING LIQUORS

Original application filed November 23, 1927, Serial No. 235,335. Divided and this application filed January 15, 1929. Serial No. 332,724.

This invention relates to a process of recovering and utilizing valuable compounds in spent cooking liquors, and more especially liquors of the class containing sodium-sulphur compounds.

Various liquors of both acid and alkaline character containing sodium-sulphur compounds as the fiber-liberating agents have been proposed and are now being utilized 10 for the production of pulp from raw cellulosic materials, a typical alkaline liquor of this class being kraft or sulphate liquor, so called, and a typical acid liquor being sodium bisulphite liquor. Where such cooking 15 liquors are employed, it is usual to recover the valuable compounds present in the spent liquor, not only because the fiber-liberating process is thereby rendered commercially feasible, but also because legislation is 20 constantly increasing against water pollution resulting from the discharge of such liquors. Usual recovery practice involves concentrating the spent liquor resulting from digestion, then burning the combustible and 25 smelting the inorganic content of the concentrated liquor, recovering the smelt in water, and converting the smelt solution to a fresh cooking liquor. When the inorganic content of spent liquors containing sodium-sulphur compounds is smelted, a smelt 30 consisting of a mixture of essentially only two sodium compounds is produced, one being sodium carbonate, and the other being a sodium-sulphur salt. Thus, if the smelting 35 takes place in a reducing atmosphere, a smelt containing sodium carbonate and sodium sulphide results; but if the smelting takes place in an oxidizing atmosphere, a smelt containing sodium carbonate and sodium sulphate results.

I have found that it is often advantageous to remove sodium carbonate from the rest of the smelt before preparing fresh cooking liquors. In accordance with the present invention, the removal of sodium carbonate 45 from the rest of the smelt is effected either by taking advantage of the difference in solubility between the sodium carbonate and the rest of the smelt, or by converting it into 50 the relatively insoluble bicarbonate. Thus,

if the smelt has been produced in a reducing atmosphere and contains sodium carbonate and sodium sulphide, separation of sodium carbonate may be effected by taking advantage of the marked difference in water 55 solubility between sodium carbonate and sodium sulphide, the sodium sulphide being quite soluble even under conditions when sodium carbonate is relatively quite insoluble and crystallizes out of solution. If the 60 smelt has been produced in an oxidizing atmosphere and contains sodium sulphate rather than sodium sulphide, separation of a substantial amount of the sodium carbonate may be effected by crystallizing it out 65 of the solution while permitting most of the sodium sulphate to remain in solution. Or the smelt solution may be carbonated to convert a portion or all of the sodium carbonate into insoluble bicarbonate and the insoluble bicarbonate removed.

The present application is a division of my application Serial No. 235,335, filed November 23, 1927, which deals with a process 75 in which smelting of the inorganic content of spent liquors such as described is effected in an oxidizing atmosphere.

The accompanying drawing illustrates diagrammatically and conventionally certain instrumentalities which may be employed when smelting is effected in an oxidizing atmosphere.

Referring to the drawing, 20 represents a storage tank containing the concentrated spent liquor, which may, for example, be 85 concentrated spent kraft liquor, sulphite liquor, or mixtures thereof. The liquor is fed into a smelting furnace 30, in which an oxidizing atmosphere is maintained so as to produce a smelt containing sodium sulphate and sodium carbonate. The smelt is run into a body of water maintained in a dissolving tank 31, to form an aqueous smelt solution.

A substantial amount of sodium carbonate 95 may then be crystallized out of the smelt solution while permitting most of the sodium sulphate to remain in solution. Thus, a smelt solution comprising 29 parts of sodium carbonate and 13 parts of sodium 100

sulphate at a temperature of, say, 30° C., may be cooled to, say, 20° C., to form a crystalline precipitate of sodium carbonate containing but a relatively very small amount of sodium sulphate. After the removal of the crystalline material, the mother liquor contains 16 parts of sodium carbonate and 12 parts of sodium sulphate, indicating a substantial removal of sodium carbonate and a relatively low removal of sodium sulphate. Or I may deliver the smelt solution (or the mother liquor) into a carbonating tower 32, as shown, wherein it is treated with carbon dioxide, thereby precipitating the relatively insoluble sodium bicarbonate. The precipitated sodium bicarbonate may be removed as by passing the solution and precipitate into a rotary filter 33. The removed sodium carbonate or bicarbonate may be acidified to produce an acid sulphite cooking liquor, while the sodium sulphate-containing mother liquor may be delivered to a kraft mill to replace the salt-cake ordinarily there employed to compensate for losses. Or only a portion of the mother liquor may be used for this purpose in a kraft mill, the rest being mixed with the sodium bicarbonate and the mixture acidified with sulphur dioxide to produce an acid cooking liquor wherein the ratio of sulphite to sulphate is higher than would be the case if the smelt solution were acidified without previous separation of bicarbonate. During acidification of the bicarbonate to produce sodium sulphite, carbon dioxide is liberated. This carbon dioxide may be recovered and used for the carbonation of other smelt solutions.

Having thus described certain embodiments of this invention, it is evident to those skilled in the art that various changes and modifications might be made therein without departing from the spirit or scope of invention as defined in the appended claims.

45 I claim:

1. A process which comprises smelting the inorganic content of spent cooking liquor containing sodium-sulphur compounds in an oxidizing atmosphere to produce a smelt containing sodium carbonate and sodium sulphate, forming an aqueous smelt solution, carbonating the smelt solution to precipitate sodium bicarbonate, and removing the precipitated bicarbonate.
- 55 2. A process which comprises smelting the inorganic content of spent cooking liquor containing sodium-sulphur compounds in an oxidizing atmosphere to produce a smelt containing sodium carbonate and sodium sulphate, forming an aqueous smelt solution, carbonating the smelt solution to precipitate sodium bicarbonate, removing the precipitated bicarbonate, and acidifying the bicarbonate to produce an acid cooking liquor.

3. A process which comprises smelting the inorganic content of spent cooking liquor containing sodium-sulphur compounds in an oxidizing atmosphere to produce a smelt containing sodium carbonate and sodium sulphate, forming an aqueous smelt solution, carbonating the smelt solution to precipitate sodium bicarbonate, removing the precipitated bicarbonate, acidifying the bicarbonate to produce an acid cooking liquor, and carbonating other smelt solution with the carbon dioxide liberated during acidification.

4. A process of recovering the valuable inorganic compounds from spent cooking liquor containing sodium-sulphur compounds for use in both acid and kraft cooking, which comprises smelting the inorganic content of such spent cooking liquor in an oxidizing atmosphere to produce a smelt containing sodium carbonate and sodium sulphate, forming an aqueous smelt solution, carbonating the smelt solution to precipitate sodium bicarbonate, removing the precipitated bicarbonate and converting the same into acid sulphite cooking liquor, and smelting the inorganic content of the remaining smelt solution along with the inorganic content of spent kraft liquor for the production of fresh kraft cooking liquor.

5. A process of recovering the valuable inorganic compounds from spent cooking liquor containing sodium-sulphur compounds for use in both acid and kraft cooking, which comprises smelting the inorganic content of such spent cooking liquor in an oxidizing atmosphere to produce a smelt containing sodium carbonate and sodium sulphate, forming an aqueous smelt solution, carbonating the smelt solution to precipitate sodium bicarbonate, removing the precipitated bicarbonate, smelting the inorganic content of a portion of the remaining smelt solution along with the inorganic content of spent kraft liquor for the production of fresh kraft cooking liquor, mixing the rest of the smelt solution with the bicarbonate, and converting the mixture into an acid cooking liquor.

6. A process which comprises smelting the inorganic content of spent cooking liquor containing sodium-sulphur compounds in an oxidizing atmosphere to produce a smelt containing sodium carbonate and sodium sulphate, and removing sodium carbonate from the smelt.

7. A process which comprises smelting the inorganic content of spent cooking liquor containing sodium-sulphur compounds in an oxidizing atmosphere to produce a smelt containing sodium carbonate and sodium sulphate, forming an aqueous smelt solution, and crystallizing out a substantial amount of sodium carbonate from

the smelt solution while permitting most of the sodium sulphate to remain in solution.

8. A process which comprises smelting the inorganic content of spent cooking liquor containing sodium-sulphur compounds in an oxidizing atmosphere to produce a smelt containing sodium carbonate and sodium sulphate, forming an aqueous smelt solution, crystallizing out a substantial amount of sodium carbonate from the smelt solution while permitting most of the sodium sulphate to remain in solution, removing the crystallized carbonate, and acidifying the carbonate to produce an acid cooking liquor.

In testimony whereof I have affixed my signature.
